THREAD CONTROL ON AUTOMATIC LOOMS

Richard G. Turner, Worcester, Mass., assignor to
 Crompton & Knowles Loom Works, Worcester,
 Mass., a corporation of Massachusetts

Continuation of application Serial No. 428,459,
 January 28, 1942. This application December
 14, 1942, Serial No. 468,929

25 Claims. (Cl. 139—256)

This is a continuation of my application Serial No. 428,459, filed January 28, 1942.

This invention relates to improvements in thread controlling mechanisms for weft replenishing looms and it is the general object of the invention to prevent interference with the operation of the thread holder by the thread of a bobbin which is discharged from the magazine due to revocation of a called replenishing operation.

In multi-color weft replenishing looms employing stationary magazines the reserve bobbins are arranged in stacks or groups and move as called one at a time to transfer position. When in transfer position the bobbin must either be transferred into the depleted shuttle or be ejected from the magazine so that it will not interfere with another bobbin moving toward transfer position. Heretofore I have proposed a pneumatic thread holder which holds the weft ends of the reserve bobbins taut by the action of a partial vacuum. In the usual operation of such a mechanism the maximum length of thread which the holder must remove from the loom is no more than the distance from the thread holder to the adjacent selvage and such a length of thread will not interfere with the proper operation of the thread holder.

When a pneumatic thread holder is applied to the so-called stationary magazine, however, the whole mass of weft on the full discharged bobbin is likely to be drawn into the thread holder with resultant objectionable clogging of the thread intake mouth of the holder. It is an important object of my present invention to provide means for cutting the thread of a bobbin discharged from the magazine to avoid clogging of the thread holder.

In the type of magazine to which my invention more particularly relates the bobbins are held in reserve stacks and the bottom bobbin of each stack is released to fall to transfer position on yielding supports, and if transfer is completed the bobbin moves to transferred position in the shuttle, but if transfer is revoked the bobbin falls to discharged position in the bobbin can. The weft end extending to the thread holder drops with its bobbin to each of these positions, but when the bobbin is correctly transferred there is no need for cutting its thread, otherwise the shuttle would not be threaded. It is only when the bobbin is in discharged position that the cutting is necessary, and in falling into the can the bobbin pulls its weft end downwardly to locate the latter within the zone of operation

of the thread cutter. While I have described specifically the relation between the various positions of the thread of a reserve bobbin and the thread cutter with reference to a multi-color magazine, yet I do not wish to be limited in the practice of my invention to such magazines, inasmuch as it is sufficient for the purposes of my invention if the thread of a properly transferred bobbin is held above or otherwise out of the range of operation of the cutter and the thread of a revoked or discharged bobbin moves into cutting position.

When a transfer is revoked the magazine is likely to be set for another transfer shortly thereafter because the shuttle which called for the first transfer will still be empty and will call for the second transfer through the weft detector. If the thread from the expelled bobbin released for the first transfer remains attached to the thread holder it is in such position as to interfere with proper tensioning and removal of the thread of the bobbin involved in the second transfer. It is a further object of my present invention to prevent interference in the removal of the thread of the second bobbin by the thread of the discharged first bobbin by cutting the latter thread before the time arrives in the cycle of loom operations when removal of the thread of the second bobbin may be necessary.

The magazine of reserve bobbins is ordinarily located above the lay and the weft ends of the reserve bobbins extend downwardly toward the thread holder. When a bobbin is discharged from the magazine in a revoking operation its thread extends downwardly from the thread holder into the bobbin can and is therefore away from the space occupied by the other weft ends. It is a further object of my present invention to provide thread cutting mechanism having a range of action below the zone occupied by the weft threads of the reserve bobbins in the magazine and the thread of a transferred bobbin but in position to sever the thread of a discharged bobbin.

With these and other objects in view which will appear as the description proceeds, my invention resides in the combination and arrangement of parts hereinafter described and set forth in the claims.

In the accompanying drawing wherein a convenient embodiment of my invention is set forth, Fig. 1 is a side elevation of a portion of a weft replenishing loom made according to my present invention,

Fig. 2 is a detailed horizontal section on an enlarged scale on line 2—2, Fig. 1.

Fig. 3 is a detailed side elevation looking in the direction of arrow 3, Fig. 2.

Fig. 4 is a vertical section on line 4—4 of Fig. 3.

Fig. 5 is a detailed plan on an enlarged scale looking in the direction of arrow 5, Fig. 1.

Fig. 6 is a view from the center of the loom looking toward the weft replenishing mechanism used in connection with my invention, and

Fig. 7 is a front elevation looking in the direction of arrow 7, Fig. 1.

Referring to the drawing, a loom frame 10 supports a top or crank shaft 11 rotating each pick of the loom and attached by means of a connector 12 to a lay L. A shuttle S is received by a shuttle box 13 on the lay and is picked back and forth across the loom in the usual manner. As shown in Fig. 2 a picker stick 15 actuates a picker 16 which engages the tip end of the shuttle S.

The magazine M is represented as being of the four-color type and has four different stacks 17 of reserve bobbins. The magazine has an inner plate 18 provided with a foot 19 secured to the loom frame and carrying front bobbin butt support 20 which may be made according to Brouwer Patent No. 1,652,604. A back bobbin support 21 may be made according to Ryon Patent No. 1,366,950 and cooperates with the front support to hold the head or butt end of the bobbin in transfer position. The outer plate 22 of the magazine may be provided with bobbin tip supports 23 made according to Ryon Patent No. 1,563,592. The butt supports are normally in open position but move to closed position when the magazine is set for transfer to hold a bobbin released from any of the stacks 17 in transfer position under a transerrer arm 24 pivoted on a stud 25 carried by the foot 19. The rear support 21 has associated therewith a cam 26 which cooperates with a pin 27 on a shuttle feeler 28 which is normally in raised position to cause the pin to engage the cam and move the support 21 rearwardly or to the left as viewed in Fig. 6 to open position. When the magazine is set for transfer the shuttle feeler is lowered and pin 27 moves down to permit the rear support 21 to move forwardly to closed or bobbin supporting position.

The loom is provided with an air pump 30 having a piston 31 attached by rod 32 to lever 33 swinging about a fixed pivot 34. An operating rod 35 connects lever 33 with the lay L to move the piston 31 rearwardly on each backward stroke of the lay. A tube 36 connects the pump to a hollow thread accumulator 37 the lower end of which has a passage 38 communicating with a pneumatic thread holder 39. The latter has an intake mouth 40 communicating with the interior of the air tight accumulator 37 to receive the weft ends W which extend from the reserve bobbins B in the magazine. As the lay moves rearwardly a partial vacuum is created in the accumulator the effect of which is to draw the weft ends through the mouth 40 and hold them taut.

The matter thus far described is constructed and operates in the usual manner. The lay swings forwardly each pick of the loom to move its bunter 43 toward a latch 42 pivoted on the transerrer arm and normally down. On the rearward stroke of the lay a partial vacuum is created within the accumulator 37 and the weft ends W are held taut. When a replenishing operation of the loom is called a bobbin is released from one or another of the stacks 17 and falls

to a transfer position on the supports 20, 21 and 23 as shown at T in Fig. 6 and the shuttle feeler is down. At the same time the latch 42 is raised into the path of the bunter 43, and as the lay advances the bobbin on the supports will either be moved to transferred position in the shuttle if the latter is properly positioned, or the called transfer will be revoked by the shuttle feeler. If the transfer is completed the weft end extends from the shuttle to the thread holder and on the immediately following pick the new bobbin and shuttle will travel together to the opposite side of the loom and there will be at least a partial threading of the shuttle eye due to holding of the thread of the transferred bobbin by the thread holder. If, on the other hand, the shuttle should be improperly boxed it will raise the shuttle feeler to prevent transfer in the usual manner and lift pin 27 against cam 26 to rock support 21 rearwardly and release the bobbin from position T and cause it to fall into bobbin can C.

In its downward course through the positions described the descending bobbin will carry its weft end from the full line position in Fig. 7 to the transfer position shown in dot and dash lines, then to the transferred position shown in light dotted lines if transfer is completed, or to the heavy dotted line position W' if transfer is revoked and the bobbin moves to discharged position. The thread holder acts to hold the weft end taut during descent of the bobbin.

The pin 27 and cam 26 are illustrated as one means for effecting discharge of an untransferred bobbin from the magazine, but I do not wish to be limited to such structures for accomplishing this result, since it is sufficient for the purposes of my present invention if the bobbin in transfer position which fails to be transferred is discharged from the magazine. Another means for accomplishing this result is shown in Gordon Patent No. 932,119.

In carrying my present invention into effect I provide means for cutting the weft end W' of the discharged bobbin at some point between the latter and the thread holder. To accomplish this result I mount a plate 50 on the bottom of the thread holder 39 and fix thereto a stationary cutter blade 51 which cooperates with a movable blade 52 pivoted on a stud 53 depending from the plate 50. A torsion spring 54 has the upper end thereof attached to the movable blade and the lower end connected to a collar 55 adjustably fixed to the stud 53 and serves to hold the movable blade in open or forward position, as shown in full lines, Fig. 5.

An operating rod 60 is pivoted as at 61 to the movable blade and extends rearwardly through a clip 62 secured as at 63 to the lay and having an opening 64 through which the rod 60 extends. A nut or abutment 65 adjustable on rod 60 behind the clip 62 is engaged by the latter on each backward stroke of the lay to cause rearward movement of the blade 52 to the cutting or dotted line position of Fig. 5 by a force communicated thereto from the lay through clip 62 and rod 60.

As shown in Fig. 7 the weft end of a bobbin in the magazine, in transfer position, or in transferred position in the shuttle, is above the range of action of the movable cutter blade and the latter therefore has no effect on a thread in these positions. When the bobbin falls into the can, however, its weft W' extends downwardly into the bight between the cutter blades and therefore within the range of operation of the thread cut-

ter. If desired the thread holder may have secured thereto an angle plate 70 lying over the cutter blades and having inclined edges to define a notch 72 which guides the thread W' into the path of the movable cutter blade. In order to prevent injury to the weaver I provide a guard 75 above the cutter. This guard comprises wire fingers 76 secured to angle plate 70 by screw 77 and diverging as suggested in Fig. 2 from notch 72 to direct the weft W' toward cutting position. The wires are close enough together to prevent the weaver's fingers from reaching the range of action of the cutter when putting new bobbins in the magazine and placing their weft ends near the mouth 40 of the thread holder.

It is believed that the operation of my invention will be understood from the foregoing description. When a called transfer is completed in the usual manner the weft thread of the descending bobbin remains above the range of operation of the thread cutter and is held taut by the thread holder during the ensuing pick of the shuttle. When a transfer is revoked, however, the rejected bobbin drops into the can and carries its weft end downwardly into the range of action of the movable cutter blade, the notch 72, if used, assisting in directing the weft end to cutting position. On the backward stroke of the lay the clip 62 strikes the abutment 65 to move the cutter blade 52 rearwardly to sever the weft end W'. The abutment 65 can be set so that the last part only of the rearward stroke of the lay will be utilized in moving the blade 52, thereby affording ample time for the discharged bobbin to fall and move its thread down into cutting position. During this same backward stroke of the lay the air pump will create a partial vacuum in the thread holder and will draw into the accumulator that part of the thread of the revoked bobbin lying beyond the cutter with respect to the bobbin can. The yarn on the revoked bobbin will not be affected by the pneumatic attraction of the thread holder and the intake mouth will therefore remain free to exert proper tension on the threads of the bobbins in the magazine and for removal of the weft ends of any bobbins subsequently properly transferred.

It is to be understood that a revoked transfer will in all likelihood be followed by a second indication of exhaustion by the weft detector and the magazine will again try to replenish the depleted shuttle when the latter arrives at the replenishing side of the loom two picks later. By this time, however, the thread cutter will have cut the weft end of the previously rejected bobbin and if the second transfer is completed the weft end of the properly transferred bobbin can be removed in the ordinary manner due to the fact that the intake mouth of the thread holder is not clogged.

I have located the thread cutter on the thread holder but I do not wish necessarily to be limited to such a mounting for it, since it is sufficient if the cutter is mounted in such position that it will not cut the weft ends of a bobbin in the magazine or properly transferred into the shuttle, but will cut the weft end of the discharged bobbin.

From the foregoing it will be seen that I have provided means for preventing a pneumatic or other form of thread holder which tensions the weft ends W from unwinding all the yarn on a bobbin discharged from the magazine. It will further be seen that the thread cutter operates

in a zone which is below a thread extending from the thread holder to a bobbin properly transferred into the shuttle or to a bobbin in any higher position, but that the cutter is positioned to cut the thread which extends from the thread holder to a bobbin which has been dropped from the magazine to a position below a position occupied by a bobbin which has been properly transferred. It will also be seen that the cutter operates at a time subsequent to the release or discharge of the untransferred bobbin, and furthermore, inasmuch as it operates each pick of the loom, the weft ends W' will be cut before the magazine can be set again for transfer. The thread holder is set forth as of the pneumatic type, but certain aspects of my invention are not limited to such a holder, inasmuch as the condition which renders a cutter desirable can be created by any form of thread holder which draws the weft threads away from the magazine by exerting a constant tension on them. The thread holder set forth in Payne Patent No. 1,842,731, may, for instance, be mentioned as a type of thread holder which can be used advantageously with my present invention.

Having thus described my invention it will be seen that changes and modifications may be made therein by those skilled in the art without departing from the spirit and scope of the invention and I do not wish to be limited to the details herein disclosed, but what I claim is:

1. In a weft replenishing loom having a reserve bobbin in transfer position and provided with a weft end, the loom having provision either for transferring the bobbin into a shuttle properly placed for replenishment or dropping the bobbin to a discharged position below the level of the shuttle if the latter is improperly placed for replenishment, the weft end of the bobbin when the latter is in discharged position lying in a low position below the position said end would have occupied had the bobbin been transferred into the shuttle, a thread holder tending to unwind the weft end when the bobbin is in discharged position, and means operated by the loom and positioned to cut the weft end of a bobbin in transfer position at a point between the thread holder and bobbin when the latter is in discharged position only to prevent the thread holder from unwinding the yarn of a bobbin in discharged position.

2. In a weft replenishing loom having a reserve bobbin in transfer position and provided with a weft end, the loom having provision either for transferring the bobbin into a shuttle properly placed for replenishment or dropping the bobbin to a discharged position below the level of the shuttle if the latter is improperly placed for replenishment, the weft end of the bobbin when the latter is in discharged position lying in a low position below the position said end would have occupied had the bobbin been transferred into the shuttle, a pneumatic thread holder tending to unwind weft from the bobbin when the latter is in discharged position, and means operated by the loom to cut the weft end only when the latter has been moved to said low position by movement of the bobbin to discharged position and thereby prevent the thread holder from unwinding the yarn of a bobbin in discharged position.

3. In a weft replenishing loom having a reserve bobbin in transfer position and provided with a weft end, the loom having provision either for transferring the bobbin into a shuttle properly

placed for replenishment or dropping the bobbin to a discharged position below the level of the shuttle if the latter is improperly placed for replenishment, the weft end of the bobbin when the latter is in discharged position lying in a low position below the position said weft end would have occupied had the bobbin been transferred into the shuttle, a thread holder to which is attached the weft end of the bobbin and acting to maintain the thread taut whether the bobbin be in the shuttle or in discharged position, and means operated by the loom and operative to cut the weft end only when the bobbin is in said discharged position.

4. In a weft replenishing loom having a magazine containing reserve bobbins provided with weft ends and having provision operative upon exhaustion of weft in a shuttle to call for a transfer operation and either insert a reserve bobbin from the magazine into the shuttle if the latter is properly placed for replenishment or drop a bobbin to a low position below that occupied by the shuttle should the called transfer operation be revoked due to displacement of the shuttle from proper replenishing position, a thread holder attached to the weft ends of the bobbins whether the latter be in the magazine, have been transferred into the shuttle, or have been dropped to said low position, and a thread cutter operated by the loom and having a range of action below a weft end which extends from the thread holder either to a bobbin in the magazine or to a bobbin transferred into the shuttle, a bobbin when dropping to said low position moving the weft end thereof within the range of operation of said thread cutter.

5. In a weft replenishing loom having a group of reserve bobbins each provided with a weft end and wherein the bobbins move from the group one by one either into a depleted shuttle as the result of a completed called replenishing operation of the loom or to a low position below that occupied by the shuttle if the called replenishing operation is revoked, a thread holder to which is attached the weft end of a bobbin whether the latter has been transferred into the shuttle or has been dropped to said low position, and a thread cutter operated by the loom and operative below the weft end extending from a properly transferred bobbin and effective to cut only the weft end extending from the thread holder to a bobbin which is in said low position.

6. In a weft replenishing loom having a group of reserve bobbins provided with weft ends and having provision operative upon call for replenishment for effecting movement of the bobbins one by one either to a properly transferred position in a shuttle below said group or to a lower position when a called replenishing operation is revoked, a thread holder to which is attached the weft end of a bobbin either in properly transferred position or in said lower position, and a thread cutter operated by the loom and effective to cut only the thread extending from the thread holder to a bobbin in said lower position.

7. In a weft replenishing loom having a group of reserve bobbins provided with weft ends and having provision for moving the bobbins one by one from the group either to a properly transferred position in a depleted shuttle or to a low revoked position below that occupied by the shuttle, the weft end of a bobbin in properly transferred position or in said group lying in a zone above the weft end extending from a bobbin in low revoked position, and a thread cutter oper-

ated by the loom and having a range of action below said zone, a bobbin when moving to said low revoked position moving the weft end thereof into said range of action of said thread cutter.

5. In a weft replenishing loom having a weft end connected to a reserve bobbin which can occupy any one of three vertical positions the first of which corresponds to a transfer position, the second of which corresponds to a transferred position in a shuttle below the first position, and the third of which is below the second position; a thread holder to which is attached the weft end of any bobbin in any of said positions, and a thread cutter operated by the loom and operative to cut only the weft end extending from the thread holder to a bobbin in said third position.

10. In a weft replenishing loom having a weft end connected to a reserve bobbin which can occupy either of two positions the first of which corresponds to a transferred position in a shuttle and the second of which is below the first position, a thread holder to which is attached the weft end of the bobbin when the latter is in either of said positions, and a thread cutter operated by the loom and having a range of action corresponding to the weft end of a bobbin in said second position only and effective to cut the weft end of the bobbin when the latter is in said second position only.

15. In a weft replenishing loom having a weft end connected to a reserve bobbin which can occupy either of two positions the first of which corresponds to a transferred position in a shuttle and the second of which is below the first position, a thread holder to which is attached the weft end of the bobbin when the latter is in either of said positions, and a thread cutter operated by the loom and having a range of action corresponding to the weft end of a bobbin in said second position only and effective to cut the weft end of the bobbin when the latter is in said second position only.

20. In a weft replenishing loom having weft ends connected to reserve bobbins which can be moved one by one either into a depleted shuttle as the result of a completed called transfer operation or be dropped to a low position below that occupied by the depleted shuttle if a called transfer operation is revoked; and wherein provision is made for calling a second transfer operation if the first transfer operation is revoked, a thread holder to which is attached the weft end of a bobbin either in a shuttle or in said low position, and means below the position occupied by the weft end of a bobbin which has been moved into the depleted shuttle and operated by the loom subsequent to movement of a bobbin to said low position and prior to movement of a second bobbin to said low position should a second called transfer operation be revoked to cut the thread of the first bobbin in said low position at a point between said last named bobbin and the thread holder.

25. In a weft replenishing loom having a group of reserve bobbins provided with weft ends and wherein calls for transfer operations effect movement of the bobbins one by one either into a transferred position in a depleted shuttle or to a low position below transferred position should a called transfer operation be revoked; and wherein provision is made to repeat the call for a transfer operation if the first call is revoked, a thread holder to which is attached the weft end of any bobbin in said low position, and means below the weft end of a bobbin in transferred position and operated by the loom to cut the thread of the first bobbin to occupy said low position prior to the time in the cycle of the loom when another bobbin can occupy said low position.

30. In a weft replenishing loom having a reserve bobbin provided with a weft end and wherein provision is made either for moving the bobbin into a depleted shuttle at one point in the cycle of loom operations as the result of a called replenishing operation, or effecting movement of the bobbin to a low position below that occupied by the shuttle at a later point in the cycle of loom operations if the called replenishing

operation is revoked, a thread holder to which is attached the weft end of the bobbin whether the latter has been inserted into the shuttle or has moved to said low position, and a thread cutter operated by the loom at a third point in the cycle subsequent to said first two points and positioned to cut only the thread of a bobbin occupying said low position.

13. In a weft replenishing loom having a bobbin provided with a weft end and having provision either to move the bobbin to transferred position in a depleted shuttle at a given level as the result of a called transfer operation, or effect movement of the bobbin to a low position below said level when a called transfer operation is revoked, a thread holder to which is attached the weft end of the bobbin when the latter is in either of said positions, and cutter means operated by the loom and so located that the weft end moves toward but remains above the range of operation of the cutter means when the bobbin moves to and remains at said given level, the weft end being moved into said range of operation of the cutter means to be cut by the latter by the bobbin when the latter moves to said low position.

14. In a weft replenishing loom having a group of reserve bobbins provided with weft ends and wherein calls for transfer operations of the loom can occur in successive two-pick cycles of the loom, a call for transfer being followed either by movement of one of the bobbins into a transferred position in a depleted shuttle at one point in the cycle or to a low position below transferred position at another point in the cycle should the called transfer operation be revoked, a thread holder to which is attached the weft end of any bobbin in said low position, and means operated by the loom to cut the thread of a bobbin in said low position at a point in the two-pick cycle subsequent to the aforesaid points at which the bobbin is either moved to transfer position or to said low position.

15. In a weft replenishing loom having a reserve bobbin provided with a weft and the loom having a shuttle which is picked away from that end of the loom at which the bobbin is located at two-pick intervals, the loom having provision upon call for replenishment of the shuttle either to move the bobbin to a transferred position in the shuttle or cause the bobbin to move to a low position below the shuttle between two successive picking intervals if the called operation is revoked, and a thread cutter operated by the loom to cut the thread only of a bobbin in said low position and having an operation for each of said intervals.

16. In a weft replenishing loom having a reserve bobbin provided with a weft at one end of the loom and the loom having a shuttle which is picked away from said one end of the loom at two-pick intervals, the loom having provision upon call for replenishment of the shuttle either to move the bobbin to a transferred position in the shuttle or cause the bobbin to move to a low position below the shuttle if the called operation is revoked between successive picking intervals, a thread cutter positioned to cut the thread only of a bobbin in said low position, and an actuator for said cutter operated by the loom and causing said cutter to operate subsequent to movement of the bobbin to said low position to cut said weft end prior to the picking interval occurring when the shuttle is next at said one end of the loom.

17. In a weft replenishing loom having provi-

sion for discharging therefrom a bobbin in transfer position which fails to be transferred, a thread holder for the weft end of a bobbin in transfer position to hold said weft end after the bobbin has been discharged, and means operated by a part of the loom and mounted on the thread holder to cut the weft end extending from the discharged bobbin to the thread holder.

18. In a weft replenishing loom operating with a magazine having a plurality of reserve bobbins which move progressively to transfer position, means to effect discharge of a bobbin in the magazine in transfer position which fails to be transferred, a thread holder which tends to unwind the weft of a discharged bobbin, and means operated by a part of the loom to cut the thread of the discharged bobbin to prevent the thread holder from unwinding the yarn on the released bobbin.

19. In a weft replenishing loom operating with a magazine having a group of bobbins which move successively to transfer position and wherein provision is made for downward discharge from the magazine of a bobbin in transfer position which fails to be transferred, a pneumatic thread holder to receive the weft ends of the bobbins in the magazine and tending to draw said weft ends in a direction away from the bobbins and also draw the weft end of a discharged bobbin away from the latter, and means below the weft ends extending from the magazine to cut the weft and extending from the thread holder to a bobbin which has been discharged downwardly from transfer position in the magazine.

20. In a weft replenishing loom operating with a magazine having a group of bobbins which move successively to transfer position and wherein provision is made for discharge from the magazine of a bobbin in transfer position which fails to be transferred, a thread holder for the weft ends of the bobbins in the magazine to hold said weft ends in a given zone and hold the weft end of a discharged bobbin below said zone, a thread cutter having a range of action below said zone, the thread of a bobbin discharged from transfer position moving into said range due to downward motion of the discharged bobbin, and means to operate said cutter to cause the same to cut the thread of the discharged bobbin.

21. In a weft replenishing loom operating with a magazine having a group of bobbins which move successively to transfer position and wherein provision is made for discharging from the magazine a bobbin in transfer position which fails to be transferred, a bobbin can to receive a bobbin discharged from transfer position in the magazine, a thread holder acting to draw the weft ends of the bobbins in the magazine and the weft end of a discharged bobbin in the can away from their respective bobbins, and means to cut the thread extending from a discharged bobbin in the can to said thread holder.

22. In a weft replenishing loom operating with a magazine which discharges a bobbin in transfer position which fails to be transferred, a bobbin can to receive a bobbin discharged from transfer position, a thread holder tending to unwind the weft of a bobbin in the can, and means operated by a part of the loom to cut the weft end extending from a discharged bobbin in the can to said thread holder.

23. In a weft replenishing loom operating with a group of reserve bobbins which move progressively to transfer position and from which weft

ends extend, the loom having provision for discharging a bobbin in transfer position which fails to be transferred, a thread holder tending to draw the weft ends away from their respective bobbins, a thread cutter having a range of operation and operative to cut the thread of a bobbin discharged from transfer position, the thread of the discharged bobbin moving into said range due solely to movement of the discharged bobbin, when the latter is discharged, and means to operate said thread cutter subsequent to discharge of the untransferred bobbin from transfer position.

24. In a weft replenishing loom operating with a group of reserve bobbins which move progressively to transfer position and from which weft ends extend, the loom having provision for discharging a bobbin in transfer position which fails to be transferred, a thread holder to receive the weft ends of the bobbins of the magazine and the weft end of a discharged bobbin and tending to draw said weft ends away from their respective bobbins, and means mounted on the thread holder

to cut the weft end of a discharged bobbin, the last named weft end moving into position for cutting by said means due solely to movement of the bobbin thereof when the latter is discharged.

- 5 25. In a weft replenishing loom having a magazine provided with reserve bobbins from which weft ends extend to an intake mouth of a pneumatic thread holder which tends to draw the weft ends away from the bobbins, the loom having provision for discharging an untransferred bobbin in transfer position downwardly from the magazine, a thread cutter operated by the loom adjacent to the thread holder to cut the thread of a discharged bobbin, and a protective guard above the thread cutter constructed to permit the thread of a discharged bobbin to move into cutting relation with respect to the cutter but protecting the fingers of an operator from the cutter when weft ends are held adjacent to said intake mouth.

RICHARD G. TURNER.
